UNITED STATES PATENT OFFICE.

FERDINAND THIELKE, OF BROOKLYN, NEW YORK.

DESIGN FOR A HANDLE FOR BUTTON-HOOKS.

SPECIFICATION forming part of Design No. 27,736, dated October 19, 1897.

Application filed August 24, 1897. Serial No. 649,399. Term of patent 3½ years.

To all whom it may concern.

Be it known that I, FERDINAND THIELKE, a citizen of the United States, residing at Brooklyn, in the county of Kings and State of New York, have invented and produced a new and original Design for Handles for Button-Hooks and Like Articles, of which the following is a specification, reference being had to the accompanying drawing, which shows a side view of my newly-designed handle applied to a button-hook.

The principal feature of my design consists of several plain oval-shaped portions or shields, decreasing in size toward the lower end of the handle, said plain portions being bounded by raised lines or ribs and beads, the upper or outer end of the handle being shaped and decorated as shown.

Referring to the drawing, A represents a handle having the plain oval-shaped portions or shields *a b c d*, decreasing in size toward the lower end of the handle, and conforming in shape somewhat to the outline or contour of said handle. These shields are bounded by the raised lines or ribs *e* and beads *f*, the outer end of the handle being shaped and decorated as shown.

What I claim is—

The design for a handle for button-hooks, and similar articles, substantially as herein shown and described.

FERDINAND THIELKE.
